UNITED STATES PATENT OFFICE.

HERMANN SCHWACHHEIM, OF BROOKLYN, NEW YORK, ASSIGNOR OF ONE-HALF TO GUSTAV A. KIRCHNER, OF SAME PLACE.

FAUCET.

SPECIFICATION forming part of Letters Patent No. 434,094, dated August 12, 1890.

Application filed September 18, 1889. Serial No. 323,849. (No model.)

To all whom it may concern:

Be it known that I, HERMANN SCHWACHHEIM, of Brooklyn, in the county of Kings and State of New York, a citizen of the Empire of Germany, have invented certain new and useful Improvements in Faucets, of which the following is a specification.

The object of my invention is to provide a new and improved faucet which is simple in construction and at all times absolutely secure and tight, thereby avoiding all possibilities of leaking; and the further object of my invention is to provide a faucet of this kind which can be so adjusted that in whatever position the plug may be placed no liquid can pass through the faucet, thus forming a safety faucet.

In the accompanying drawings, Figure 1 is a vertical longitudinal sectional view of my improved faucet. Fig. 2 is a horizontal sectional view of the bottom plug-section on the line *x* *x*, Fig. 1. Fig. 3 is a plan view of the bottom edge of the upper tubular plug-section. Fig. 4 is a vertical longitudinal sectional view of the faucet provided with the locking attachment. Fig. 5 is a horizontal cross-sectional view on the line *y* *y*, Fig. 4, and Fig. 6 is a horizontal sectional view of the bottom plug-section on the line *w* *w*, Fig. 4. Similar letters of reference indicate corresponding parts.

The faucet shell or body *A* is provided with a spout *B*, projecting in one direction, and some distance below the same with the tubular shank *C*, projecting in the opposite direction, which shank may be screw-threaded or tapered. The casing *A* is closed at the lower end by a solid screw-cap *D* and at the upper end by a screw-cap *E*, having an aperture for the spindle *F* of the valved plug, which spindle has a suitable handle *G* or cross-piece of any well-known construction. The bore of the casing *A* is tapered from the top and bottom toward a horizontal plane about midway between the inner ends of the spout *B* and tubular shank *C*.

On the lower end of the spindle *F* the lower plug-section *H* is formed, which is tapered to fit in the lower tapered half of the bore in the casing *A*, said plug-section and spindle having a longitudinal bore *J*, which is in com-

munication with the lateral channel *K*, that can register with the bore of the shank *C*, thus adapting the liquid to pass from said tubular shank *C* through the channel *K* into the bore *J*. Near the upper part of the bore *J* a channel *L* is provided, which extends from the bore *J* to the outside of the stem. The lower end of the bore *J* is closed by a screw *M*, between which and the bottom cap *N* a spiral spring *O* is interposed, which presses the tapering plug-section *H* against the tapering sides of the lower part of the bore in the casing *A*.

In the top of the lower plug-section *H* two holes *P* are formed for receiving pins *P*, projecting from the bottom edge of the upper tapering tubular plug-section *Q*, which fits in the upper part of the tapering bore of the casing *A*, and is provided with a channel or aperture *R*, which can register with the channel or aperture *L* of the stem *F* and with the bore of the spout *B*. A washer *R'* is placed on the top of the plug-section *Q* and is pressed down by the screw-cap *E*. By turning the spindle *F* the lower plug-section *H*, made integral therewith, is turned, as is also the upper plug-section *Q*, for the reason that the pins *P* of the upper section pass into the apertures *O* of the lower section. The spring *N* at all times presses the lower plug-section closely against the bottom part of the bore of the casing *A*, and the screw-cap *E* keeps the upper section *Q* of said plug pressed against the sides of the bore, thereby forming a faucet which cannot leak and get out of order.

Instead of making the pins *P* projecting from the bottom edge of the upper plug-section *Q* permanent, they may be made removable—as, for example, (shown in Fig. 4,) the pin *P'* is formed on the lower end of the rack *a*, mounted to slide in the longitudinal aperture *b* in the upper plug-section *Q*, which rack engages the pinion *d*, mounted in the upper plug-section and adapted to be turned by means of a key *S*, which can be inserted into said pinion through an aperture *g* in the casing *A*. The apertures *O'* of the bottom plug-section are then not arranged opposite each other, but about ninety degrees from each other, as shown in Fig. 6.

When it is desired to so adjust the faucet

that the same cannot be used, the pin P' is raised and the spindle F is turned, the upper plug-section Q remaining stationary. Thereby the plug-section Q and the spindle are brought into such relative position that the apertures R and L do not register, and the aperture L is closed by the upper plug-section. The pin P' is then lowered so as to pass into the other aperture O', thereby locking the spindle and plug-section Q in the above-described positions. As the upper end of the bore of the spindle is now closed, it is impossible to draw any liquid through the faucet, it being immaterial in what position the plug is placed or turned, and the faucet cannot be used to draw liquid until the spindle and plug-section Q have been adjusted relatively to each other in such a manner that the apertures R and L register.

20 By using a faucet of this kind tampering by attendants, servants, or other persons with the faucets of barrels containing valuable and costly liquids and fluids is effectually prevented, and an effective safeguard is thus provided.

Having thus described my invention, I claim as new and desire to secure by Letters Patent—

1. The combination, with a faucet-casing having an inlet and an outlet channel and a bore which is tapered from the ends to the plane about midway between the inner ends of said channels, of a plug in said bore, which plug is composed of two tapered sections, one being connected with the stem or spindle and provided in its upper edge with apertures, and

the other section being made tubular and surrounding the stem and provided in its lower end with pins that can pass into the apertures in the upper end of the section connected with the spindle, substantially as set forth.

2. The combination, with a faucet-casing having an inlet and outlet channel, of a plug composed of two sections, the lower one of which is made integral with the stem, said plug-section and stem having a longitudinal bore, the lower plug-sections having an aperture that registers with the inlet-channel of the casing, and the upper part of the spindle-bore having an aperture that can register with the outlet-channel of the casing, and a tubular plug-section surrounding the spindle and having an aperture that can register with the aperture leading to the spindle-bore and with the outlet-channel of the casing, substantially as set forth.

3. A faucet having a plug composed of two sections, one above the other, the lower section being connected with the spindle, a pin mounted in the upper section and adapted to pass into an aperture in the lower section, and a rack and pinion for raising and lowering said pin, substantially as set forth.

In testimony that I claim the foregoing as my invention I have signed my name in presence of two subscribing witnesses.

HERMANN SCHWACHHEIM.
